UNITED STATES PATENT OFFICE

129,748

DESIGN FOR A HAT OR SIMILAR ARTICLE

Morton A. Oppenheimer, Philadelphia, Pa.

Application August 15, 1941, Serial No. 102,851

Term of patent 7 years

To all whom it may concern:

Be it known that I, Morton A. Oppenheimer, a citizen of the United States, residing at Philadelphia, in the county of Philadelphia and State of Pennsylvania, have invented a new, original, and ornamental Design for a Hat or Similar Article, of which the following is a specification, reference being had to the accompanying drawing, forming part thereof, in which:

Fig. 2 is a rear perspective view of the hat shown in Fig. 1.

I claim:

The ornamental design for a hat or similar article, as shown.

MORTON A. OPPENHEIMER.
